Specification for Design.

Patented Aug. 22, 1911.

Application filed June 1, 1911. Serial No. 630,683. Term of patent 7 years.

To all whom it may concern:

Be it known that I, FREDERICK HABENSACK, a citizen of the United States, and a resident of Sag Harbor, in the county of Suffolk and State of New York, have invented a certain new, original, and ornamental Design for a Handle for Spoons, Forks, or Similar Articles, of which the following is a specification.

In the accompanying drawing, Figure 1 is a view of the obverse side, and Fig. 2 a

view of the reverse side of the handle of a spoon or fork having my design applied thereto.

I claim:—

The ornamental design for a handle for spoons, forks, or similar articles.

FREDERICK HABENSACK.
